UNITED STATES PATENT OFFICE.

CHARLES PERCY WATSON, OF FOSSE, LEICESTER, ENGLAND.

EDUCATIONAL APPLIANCE.

1,293,586.

Specification of Letters Patent.

Patented Feb. 4, 1919.

Application filed August 24, 1918. Serial No. 251,228.

To all whom it may concern:

Be it known that I, CHARLES PERCY WATSON, a subject of the King of Great Britain, residing at 2 St. Pauls road, Fosse, Leicester, England, have invented certain new and useful Improvements in Educational Appliances, of which the following is a specification.

In educational appliances it has been proposed to provide a number of groups of separately pivoted plates, prisms or the like, hereafter in this specification termed indicators, adapted to have characters delineated upon them, each indicator being capable of being independently turned about its pivot in order to exhibit such characters or a selection of such characters to view, or to be turned so that said characters are not exposed, and in these appliances it has been hitherto considered necessary to provide frictional bearings for the pivots in order to retain the indicators in the position in which they have been set.

Now plates, prisms or the like so mounted in frictional bearings do not provide the requisite conveniences required in such educational appliances, in that for example when an educational appliance comprising a considerable number of such frictionally carried plates or indicating surfaces which have been set for illustrating some educative lesson, and have individually been so set, such indicators must separately or in groups be operated so as to return them to that position in which either all the indicators are in view, or in which all the indicators are out of view, which entails some labor as well as a loss of time, which loss is important when passing from one educative lesson to another; moreover the necessity for providing frictional bearings and other like devices for retaining the indicators in the position in which they have been placed entails a complex and correspondingly expensive construction, and moreover a construction which is subject to derangement in such uses as these appliances are calculated to have.

Now the primary object of this invention is to provide what I have termed pivoted indicators but so constructed that a suitable number may be carried in a frame, and by the mere rocking of which frame in one direction all the indicators thereon can be brought into view and so remain when the frame is returned to its normal vertical position. By rocking the frame in the other di-

rection all the indicators can simultaneously be brought into a position when the delineations thereon are out of view and the indicators will so remain when the frame is returned to its vertical position, while at the same time any individual indicator, or a number or selection of such individual indicators, can be thrown into or out of view by the lecturer simply tapping the indicator or indicators with a pointer, and this without rocking the frame.

According to this invention each indicator consists of a plate having a desired symbol delineated on its front face, and having rearwardly extending bearings which may consist of ears each formed with a hole, through which bearings or holes or through a sleeve carried by such ears, a horizontal pivot freely passes so that when the plate is approximately vertical, the center of gravity of the plate is in front of and above the axis of the pivot and the lower edge of the plate sits upon a suitable stop, while when the plate is thrown out of view, that is so that it is approximately edgewise to the observer, the center of gravity of the plate is rocked over rearward of the pivot and remains so because the center of gravity is then between the pivot and the top or rear extremity of the indicator, and the rear edge of the plate then rests on a stationary ledge of the carrying frame.

It will now be well understood that any number of such plates may be mounted within one frame, and the frame can be mounted on pivots or carried by any suitable means so that the whole frame can at times remain vertical during an educative lecture, or it can be rocked in one angular direction to bring all the plates into view, or be rocked in the opposite direction to throw all the plates out of view, and after each such movement be brought to its vertical position.

Therefore in carrying out this invention each plate is mounted freely upon a horizontal pivot which however is in a plane parallel to the plane of the plate but at a distance therefrom, so that as the plate is turned from an approximately vertical position to an approximately horizontal position, the center of gravity of the plate changes from one side of the pivot to the other transversely of its length, and therefore the plate remains in either of its positions resting against a stop until it is again rocked.

The invention is described in further detail with reference to the accompanying drawings, whereon Figure 1 is a front elevation, and Fig. 2 is a side elevation, showing 5 an example by general views of a complete apparatus.

Fig. 3 is a vertical section drawn on a larger scale than the previous figures, showing one of the plates or indicators with its 10 carrying frame in an inclined position to which it has been brought to cause the plate to rock from its approximately vertical to its approximately horizontal position.

Fig. 4 is a view similar to Fig. 3, showing 15 two of such plates in a frame in differing positions. Fig. 5 is a rear elevation of the upper plate shown at Fig. 4 detached from the framework, and Fig. 6 is a view of one of the plates showing a character delineated 20 thereon.

Referring to the example of construction shown in the accompanying drawings and primarily to Figs. 3, 4 and 5, each indicator plate 1 which may be formed of any suitable 25 material such as metal, consists as shown of a rectangular flat surface from each side of which extends a flanged ear 2, between which ears a tube 3 extends, and passing through the tube is a pivot pin 4, the ends 30 of which are fixed in a framework 5 having a horizontal partition 6 below the plate and also a rear bar 7, and of such construction, that when the frame 5 is rocked to a rearward angle as shown in Fig. 3, the plate 1 35 will be rocked about its pivot 4 until the upper portion of the plate (shown in Fig. 4) rests on the rear bar 7 as shown in Fig. 3, the center of gravity of the plate 1 being then rearward of the pivot 4, and when the 40 frame 5 is brought to a vertical position the plate will still rest upon the rear bar 7 as shown at the lower part of Fig. 4 and will remain in that position with its front face, upon which a figure or other sign is delineated, out of view of the observers who are 45 located in front of the apparatus, and preferably the lower edge 8 of the plate 1 entirely prevents the figure or the like on the front of the plate from being observed when 50 the said plate 1 is in the position shown at the lower part of Fig. 4.

By tilting the frame 5 to an opposite angle to that indicated in Fig. 3, all the plates will again assume the position of that 55 shown at the upper part of Fig. 4 when the figure or other sign delineated on its face will be in view of the observers.

Obviously the mechanical construction of the device may be varied to some extent, as 60 for instance the tube 3 may be dispensed with and the pivot 4 simply pass through the ears 2 of the plate 1.

When the plate is in its approximately vertical position as shown at the upper part 65 of Fig. 4 the forwardly bent edge 8 of the

plate 1 rests upon the front edge of the horizontal partition 6.

Fig. 5 illustrates the rear view of the plate 1 and shows the tube 3 passing from ear to ear, while Fig. 6 shows a front view 70 of a plate upon which the letter E is delineated, and obviously any appropriate letters or signs may be indicated on any such plate.

The frame 5 may be constructed to contain any required number or series of such pivoted plates as is illustrated at Figs. 1 and 2 and such a frame 5 should be mounted so that it can be rocked to the requisite angles, and in the example illustrated the frame is supported upon pivots 9 carried by two 75 standards 10, and one of the pivots is provided with a wheel 11 or a wheel may be placed at each end, or other operating means 80 may be employed which are adapted to be grasped by the hand of the user and by 85 which the frame can be rocked, and in the example shown the pivots 9 are located above the center of gravity of the frame so that normally the frame 5 will be suspended 90 in a vertical position. Means are indicated 95 such as pins 12 by which the angular movement of the frame 5 is limited in either direction. In some cases the rocking axis of the frame 5 may be central, in which case any suitable catch or grip may be provided 100 to retain the frame in its approximately vertical position.

With such an arrangement, by rocking the frame to about the dotted position 13 shown at Fig. 2 all the indicating plates 1 will be 100 placed so that the signs delineated thereon will be out of view of the observer whereas by rocking the frame into about the dotted position shown at 14 Fig. 2, all the plates 1 will be rocked into that position in which 105 their indicating faces can be observed, and from either position the frame will automatically assume its vertical position shown in full lines, in which the indicating plates will still remain in positions into which they 110 have been placed by the rocking of the frame.

It will also be observed that when the frame is in its vertical position any of the plates may be rocked from their indicating 115 positions to their negative positions, or vice versa, by being individually tapped by a pointer or the like, and will remain in the position so placed.

Obviously variations may be made in the 120 construction and type of supports for the frame 5, Figs. 1 and 2 and the means for rocking the frame 5 may be varied. Also the ears 2 of each plate have been illustrated as being formed by bending rearward a portion 125 of the plate from each side thereof, but instead thereof the ears may be produced by bending a strip of metal with its ends at right angles to its length, and fixing such strip to the rear of the plate, and forming 130

the bent ends with holes to receive the spindle 4, or eyes may be riveted or otherwise fixed to the rear of the plate to receive the spindle or the plate may be made of dimensions to permit of a bearing hole being formed through the plate itself in a proper position.

What I claim as my invention and desire to secure by Letters Patent is:—

- 10 1. In educational appliances of the kind specified; the combination of an indicator plate having a desired symbol delineated on its front face, bearings extending from the rear face of the said plate, a horizontal pivot 15 to freely pass through the said bearings to support said plate, a frame to support said pivot, said bearings being positioned on said plate so that the center of gravity thereof is in front of and above the axis of said pivot 20 when said plate is approximately vertical and is rearward of said pivot when said plate is rocked to an approximately horizontal position edgewise to the observer, a horizontal member on said frame with which 25 the lower edge of said plate contacts and upon which it rests when said plate is in its vertical position, and a rear bar on said frame rearward of said plate upon which the rear upper portion of said plate rests 30 when placed approximately edgewise to the observer.
2. In educational appliances of the kind specified; the combination of a framework, vertical and horizontal strips dividing said framework into a plurality of frames and a rear bar extending horizontally at the rear of each horizontal strip, a plurality of indicator plates each having a desired symbol delineated on its front face one plate located 35 in each of said frames, bearings extending from the rear face of each of said plates, a horizontal pivot freely passing through said rearwardly extending bearings of each plate and supported in said frame, said bearings 40 on said plate being located in such positions on the rear face thereof that when said framework is rocked from a vertical position about a horizontal axis in one direction said indicator plates will be turned by gravity 45 upon their pivots and when said framework is again vertical will remain in an approximately vertical 50 position with the lower edges of said plates resting on said horizontal dividing strips of said framework and when 55 said framework is rocked in an opposite direction and again turned to its vertical position said indicator plates will have been again rocked about their pivots by gravity and rest upon said rear bars of said frame- 60 work and there remain in position edgewise to the observer.
3. In educational appliances of the kind specified; the combination of an indicator plate having a desired symbol delineated on its front face, ears extending rearwardly at 65
- right angles from the rear face of said plate, said ears having holes formed through same at a distance from the rear face of said plate, a horizontal pivot to freely pass through the holes in said ears to support said plate about 70 which pivot said plate can freely turn, a framework to support said pivot, a horizontal member on said framework upon which the lower edge of said plate rests when approximately vertical, and a rear bar on said 75 framework rearward of said plate upon which the rear upper portion of said plate rests when approximately horizontal, said pivot being located relatively to said plate in such position that said plate when rocked about said pivot into a vertical position is 80 retained by gravity and rests on said horizontal member, and when rocked about said pivot into a horizontal position is retained therein by gravity and rests on said rear bar. 85
4. In educational appliances of the kind specified; the combination of a framework, vertical and horizontal strips dividing said framework into a plurality of frames and a rear bar extending horizontally at the rear 90 of each horizontal strip, a plurality of indicator plates each having a desired symbol delineated on its front face one plate located in each of said frames, bearings extending from rear face of each of said plates, a horizontal pivot freely passing through said rearwardly extending bearings of each plate and supported in said frame, horizontal trunnions on said framework, standards to carry said trunnions, means for rocking said 100 framework from and to a vertical position in either direction about the axis of said trunnions, said bearings on said plate being located in such positions on the rear face thereof that when said framework is rocked from a vertical position about a horizontal axis in one direction said indicator plates will be turned by gravity upon their pivots and when said framework is again vertical 105 will remain in an approximately vertical 110 position with the lower edges of said plates resting on said horizontal dividing strips of said framework and when said framework is rocked in an opposite direction and again turned to its vertical position said indicator plates will have been again rocked about their pivots by gravity and rest upon said rear bars of said framework and there remain in positions edgewise to the observer. 115
5. In educational appliances of the kind specified; the combination of an indicator plate having a desired symbol delineated on its front face, ears extending rearwardly at right angles from the rear face of said plate, a bearing tube fixed to said ears, a horizontal pivot to freely pass through said bearing tube to support said plate about which pivot said plate can freely turn, a framework to support said pivot, a horizontal member on said framework upon which the lower edge 120 125 130

of said plate rests when approximately vertical, and a rear bar on said frame rearward of said plate upon which the rear upper portion of said plate rests when approximately 5 horizontal, said pivot being located relatively to said plate in such position that said plate when rocked about said pivot into a vertical position is retained by gravity and rests on said horizontal member, and when 10 rocked about said pivot into a horizontal position is retained therein by gravity and rests on said rear bar.

6. In educational appliances of the kind specified; the combination of an indicator 15 plate having a desired symbol delineated on its front face, a forwardly extending flange on the lower edge of said plate considering same in a vertical position, bearings extending from the rear face of said plate, a horizontal pivot to freely pass through the said 20 bearings to support said plate, a frame to

support said pivot, said bearings being positioned on said plate so that the center of gravity thereof is in front of and above the axis of said pivot when said plate is approximately vertical and is rearward of said pivot when said plate is rocked to an approximately horizontal position edgewise to the observer, a horizontal member on said frame with which the lower flanged edge of said plate contacts and upon which it rests when said plate is in its vertical position, and a rear bar on said frame rearward of said plate upon which the rear edge of said plate rests when placed approximately edgewise to the observer. 25 30 35

In witness whereof I have hereunto set my hand in the presence of two witnesses.

CHARLES PERCY WATSON.
